(57) **CLAIM**

The ornamental design for an inkjet printer with photographic media supply tray, fixed sheet feeder, and window access door, substantially as shown and described.

DESCRIPTION

FIG. 1 is a perspective view of an inkjet printer with photographic media supply tray, fixed sheet feeder, and window access door, in accordance with the present invention;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and,

FIG. 7 is a right side elevational view thereof.

The dashed lines in FIGS. 1-3, 5 and 7, are for illustrative purposes only and form no part of the claimed design.
